UNITED STATES PATENT OFFICE.

ARTHUR C. LIVERMORE, OF HOLYOKE, MASSACHUSETTS, ASSIGNOR TO THE AMERICAN THREAD COMPANY, OF NEW YORK, N. Y., A CORPORATION OF NEW JERSEY.

SPOOL-FINISHING MACHINE.

984,680.

Specification of Letters Patent. Patented Feb. 21, 1911.

Application filed October 6, 1906. Serial No. 337,842.

To all whom it may concern:

Be it known that I, ARTHUR C. LIVERMORE, a citizen of the United States, residing at Holyoke, Hampden county, Massachusetts, have invented certain new and useful Improvements in Spool-Finishing Machines, of which the following is a full, clear, and exact description.

My invention relates to improvements in spool finishing machines and has for its object to produce a machine for automatically finishing the heads of pulp spools so as to reduce them to a definite predetermined size and give their peripheral surfaces a smooth 15 finish.

The following is a description of a machine embodying my invention, reference being had to the accompanying drawings in which—

20 Figure 1 is a front elevation of the machine showing the supporting table in section, Fig. 1^a is a plan view, with the hopper removed, Fig. 2 is a cross-section of the machine on the line X—X, Fig. 1, Fig. 3 is 25 a cross section of the machine on the line Y—Y, Fig. 1, Figs. 4, 5, 6 and 7 are enlarged views of the details.

Referring more particularly to the drawings, A is a cam shaft provided with cams 30 A', A², having respectively complementary grooves B B' and C C'. The left hand cam A' is provided with a third groove D. The shaft A is also provided with a carrier-actuating cam E for the purpose hereinafter 35 described. This shaft A is revolved by a worm wheel F driven from any suitable source.

In journals upon the table of the machine are mounted two reamer shafts G G' which 40 are made to revolve at a desired rate by belts upon pulleys H H'. These shafts are surrounded by loose collars I I' adjusted by nuts I² I³. To the collars I I' are pivoted levers J J', the lower ends of which levers 45 are provided with anti-friction rollers traveling in the grooves C C'. These reamer shafts G G' are provided with reamers K K'. 50

L L' are the heads of clamping devices which pass through the stationary journals of the shafts G G' and have their rear ends connected to forks l l' on the shafts G G'. These forks lie between shoulders l³ upon the shafts G G' and the pulleys H H' so as to partake of the longitudinal movement of 55 these shafts while being prevented from

turning by their bearings in the stationary journals. The heads L L' are mounted on rods L² which enter the tubes L³ and are forced outwardly by the springs L⁴ so as to offer pressure to any object in contact with 60 which they may be brought.

When a bobbin comes between the reamer ends of the shafts G G' the reduced portions of the reamers K K' enter the holes of the bobbins so as to center it. On a further inward movement of the shafts G G', the clamps L L' engage the bobbin and prevent it from turning. Upon a further inward movement of the shafts G G', the straight cutting portions of the reamers K K' 70 ream the ends of the holes within the bobbin to the desired size, the cutting shoulder portion k' of the reamers then cuts off the edge of the hole and eliminates the bur.

Above the reamer shafts G G' and slightly 75 to the rear are two revolving clamping shafts M M' having clamping surfaces M² M³. These shafts are provided with pulleys N N' so as to be belt-driven at a rapid rate. They are also provided with loose adjustable 80 collars O O' to which are connected levers P P' having at their lower ends anti-friction rollers which enter the cam grooves B B'. The collar O' is provided with a spring connection o' which takes up any unevenness in 85 the length of the spools. The cam grooves B B' are so constructed that when the bobbin is placed between the clamping surfaces M² M³, the clamping shafts M M' are brought together sufficiently to firmly grasp 90 the bobbin and cause it to revolve.

M⁴ M⁵ are doffers or knock-off devices assisting in centering a bobbin between the clamping surfaces M² M³ and doffing it when the spindles are withdrawn. Mounted in 95 ways upon the table of the machine is a sliding base Q provided with bearings Q' in which is mounted a revolving shaft Q² carrying two finishing or grinding disks Q³ Q⁴ adapted when moved longitudinally to engage 100 the periphery of revolving bobbins held between the clamping surfaces M² M³. This table Q is provided with a depending lug R to which is connected a lever S fulcrumed at S' and provided at its other end with an anti-friction roller which travels 105 in groove D. The revolution of the cam groove D causes the lever S to move the table Q to and fro in the direction of the axis of the shaft Q², thus bringing the fin- 110

ishing surfaces Q^3 Q^4 up against the sides and onto the peripheries of the two heads of the revolving spool.

The spools are primarily contained in a 5 hopper T and are automatically released so as to be carried by gravity to the reamers, from thence they are carried to the clamping surfaces M^2 M^3 by a carrier U mounted on an arm pivoted at U' and actuated by a 10 link U² which in turn is actuated by a counterweight lever U³ carrying an anti-friction roller U⁴ which bears against the cam E. The spring U⁵ and counterweight U⁶ keep the roller U⁴ in engagement with 15 the cam E.

Beneath the reamers is a stationary receiver or holder K² which catches the heads of a falling bobbin and holds it in position while the tapered ends of the reamers are 20 entering the holes to be reamed. The bobbins are retained in the hopper T by an upward projection T' which is pivotally mounted on a stationary arm. A spring T² tends to hold it up in the path of the bobbins in the 25 hopper, while a chain T³ connected to the link U² of the carrier withdraws it when the carrier is in depressed position.

In the operation of the machine the revolution of the cam E brings the carrier U in 30 position so as to lift a bobbin from the holder K², whereupon being released from the hopper, it falls into the support K² and is held with its holes in alignment with the reamers K K'. The reamers K K' are then 35 forced inwardly under the action of the cam grooves C C' so as to ream the ends of the holes of the binder and are then withdrawn. Thereupon a further movement of the cam E moves the carrier so as to pick up the 40 bobbin and bring it between the clamping surfaces M^2 M^3 where it is held until the clamping surfaces M^2 M^3 engage therewith. Thereupon the carrier U is withdrawn and returned to a position to pick up another 45 bobbin from the support K². While the bobbin is held between the clamping surfaces M^2 M^3 , the sliding base Q through the action of the cam groove D and lever S is moved longitudinally so as to bring the 50 finishing surfaces Q^3 Q^4 against the sides and peripheries of the revolving bobbin, thereby grinding them to size and finishing them as desired. The sliding base Q is then withdrawn to its original position. The 55 clamping surfaces M^2 M^3 are withdrawn and, the carrier being in depressed position, the bobbin when released thereby is dropped upon the guiding surface B' and is conveyed to the rear of the machine. The machine 60 is automatic in its action it requiring only that the hopper T be kept filled with bobbins. On account of the slight attention necessary, one attendant can look after a number of such machines and thereby the 65 work can be greatly expedited and the cost

of labor much reduced. The machine is simple in its construction and accurate in its operation and can be adapted for various uses as may be desired.

The grinding surfaces Q^3 Q^4 where the 70 machine is used for grinding or finishing objects made of compressed wood pulp, I preferably make of carborundum glued or cemented to the surfaces in any suitable manner. The carborundum may be made of 75 varied degrees of coarseness depending upon the fineness of the finish desired.

The finishing devices Q^3 Q^4 have tapered and cylindrical portions, both of which are covered with carborundum, so that the spool 80 heads are first engaged by the tapered surfaces and thus gradually reduced to the desired size. The front face of the rim Q^5 on the finishing device Q^3 is also provided with a carborundum coating, so as to finish a 85 circle on one end of the spool.

What I claim is:

1. In a finishing machine, the combination of a revolving clamp having a fixed axis of revolution, said clamp being concentric with 90 its axis of revolution, a revolving finishing device whose surface of revolution has a tapered portion and a cylindrical portion, and means for producing a relative longitudinal movement between the finishing device and 95 the clamp parallel to the axis of said clamp, the axis of said finishing device being out of alignment with and parallel to the axis of said clamp.

2. In a machine for finishing spools, the 100 combination of a revolving clamp having a fixed axis of revolution, said clamp being concentric with its axis of revolution, a revolving finishing device consisting of two members each having tapered finishing portions facing in the same direction, and means for producing a relative longitudinal movement between said finishing device and said 105 clamp parallel to the axis of said clamp, the axis of said finishing device being out of alignment with the axis of said clamp.

3. In a machine for finishing spools, the combination of a revolving clamp having a fixed axis of revolution, said clamp being concentric with its axis of revolution, a 115 revolving finishing device consisting of two members, each having a tapered portion and a cylindrical forming portion, means for producing a relative longitudinal movement between said finishing device and said clamp parallel to the axis of said clamp, the axis of 120 said forming device being out of alignment with the axis of said clamp.

4. In a machine for finishing spools, the combination of a revolving clamp having a 125 fixed axis of revolution, said clamp being concentric with its axis of revolution, a revolving finishing device having a surface of revolution in part tapered and in part cylindrical and in part at right angles to its axis, 130

the part at right angles extending beyond the cylindrical part and means for producing a relative longitudinal movement between said finishing device and said clamp 5 parallel to the axis of said clamp, the axis of said finishing device being out of alignment with the axis of said clamp.

5. In a finishing machine, the combination of a carrier lifting objects to be finished one 10 at a time, a revolving clamp concentric with its axis of revolution, means for causing said carrier to convey said objects to said clamp, means for causing said clamp to grasp and release said objects, a revolving finishing device 15 adapted to be brought into engagement with said object while in said clamp, and a chute carried by said carrier for guiding the objects when released by said clamp, being beneath said clamp when said carrier is in 20 depressed position and said clamp releases said objects.

6. In a finishing machine, the combination of a hopper, a receiver to which objects to be finished are delivered one at a time, a carrier lifting said objects from said receiver, 25 a revolving clamp concentric with its axis of revolution, means for causing said carrier to convey said objects to said clamp, means for causing said clamp to grasp and release said objects, a revolving finishing device 30 adapted to be brought into engagement with said object while in said clamp, and a chute carried by said carrier for guiding the objects when released by said clamp, being beneath said clamp when said carrier is in 35 depressed position and said clamp releases said objects.
